HAIR CURLER

Ross McCray McFadden, Hollywood, Calif.

Application August 5, 1949, Serial No. 4,320

Term of patent 14 years

(Cl. D86—10)

To all whom it may concern:

Be it known that I, Ross McCray McFadden, a citizen of the United States and a resident of Hollywood, in the county of Los Angeles and State of California, have invented a new, original, and ornamental Design for a Hair Curler, of which the following is a specification, reference being had to the accompanying drawing, forming part thereof, in which:

I claim:

The ornamental design for a hair curler, as shown.

ROSS McCRAY McFADDEN.
